DESIGN FOR A HANDBAG

Daniel Rubin, New York, N. Y.

Application June 8, 1944, Serial No. 113,923

Term of patent 3½ years

(Cl. D87—3)

To all whom it may concern:

Be it known that I, Daniel Rubin, a citizen of the United States of America, residing in New York city, county of New York, and State of New York, have invented a new, original, and ornamental Design for a Handbag, of which the following is a specification, reference being had to the accompanying drawing, forming part thereof, wherein,

Figure 3 is a rear elevational view of the handbag, drawn on a smaller scale, with a portion of the handle omitted for convenience of illustration.

I claim:

The ornamental design for a handbag, substantially as shown, and described.

DANIEL RUBIN.
